(57) **CLAIM**

The ornamental design for a wire cage for containing an animal, as shown and described.

DESCRIPTION

FIG. 1 is a perspective view of a wire cage for containing an animal that illustrates the novel design;

FIG. 2 is a top view thereof;

FIG. 3 is a left side elevational view thereof;

FIG. 4 is a right side elevational view thereof;

FIG. 5 is a bottom view thereof;

FIG. 6 is a front view thereof; and,

FIG. 7 is a back view thereof.
